RECEPTACLE OPENER

Henry E. Frankenberg, Toledo, Ohio, assignor to
 Owens-Illinois Can Company, a corporation of
 Delaware

Application June 1, 1940, Serial No. 338,389

4 Claims. (Cl. 220—43)

The present invention relates to improvements in can openers of the lever type adapted for lifting and removing friction lids from receptacles and more particularly to an opener adapted to be permanently attached to the lid.

Friction type lids are usually employed on cans, canisters and drums from which the contents may be removed a little at a time, thereby necessitating repeated opening and resealing of the container. It is thus the primary object of the invention to provide an opener permanently attached to the lid for readily and easily removing it and which does not interfere with the closing and resealing of the container.

It is also an object of the invention to provide a lever type opener slidably attached to the usual peripheral bead of a friction lid which may be readily moved to different positions for prying and removing it.

Another object of the invention is to provide a lid lifter secured to the peripheral bead of a friction type lid and overlying it whereby said lifter in no way obscures or otherwise hides any printing or identifying marking on the lid.

A further object is the provision of an opener which is relatively inexpensive to manufacture and is readily applicable to either single, double or full friction type plugs or lids.

Other objects will be in part apparent and in part pointed out hereinafter.

In the drawing:

Fig. 1 is a fragmentary perspective view of a receptacle having a full friction type lid to which my invention is applied.

Fig. 2 is a side elevational view of the lifter in inoperative or closed position.

Fig. 3 is a plan view thereof.

Fig. 4 is a sectional end view of the lifter taken substantially on line 4—4 of Fig. 2.

Fig. 5 is a similar view of the lifter shown applied to a single friction type lid.

Figs. 6 and 7 illustrate a modified form of my invention; Fig. 6 being a side view thereof and Fig. 7 is an end view of the lifter shown in Fig. 6.

The lid lifter illustrated herewith in Fig. 1 is shown in connection with a lid 10 of full friction type having a peripheral bead 11 which overlies a bead 12 formed on the can body 13. The lifter which is a simple lever, is formed of relatively stiff sheet metal and comprises generally a body portion 15 having formed at one end thereof, a key 16 or spreader, and disposed oppositely therefrom, a retaining guide finger 17. A finger piece 18 formed on the opposite end of the body and projecting radially inward, provides means by which

the lifter may be rocked about a fulcrum formed by said key member 16 as will become apparent presently. In the preferred form of the invention, the body portion 15 includes an elongated flat strip 20, an outer integral depending side wall 21 (Fig. 2) and an inner depending side wall 22, of which the retaining guide finger 17 forms a part. The side walls 21 and 22 are curved in the direction of their length and together with said strip 20, form a channel 23, the whole of which straddles the bead 11 of the lid (Fig. 4).

The wall 22 of the lifter, is disposed in close proximity to the side sealing wall of the can lid and the lower margin thereof projects well within a circular groove 25 formed in the surface of the lid 10 where it joins the side sealing wall. At least a portion of the guide 17 (Fig. 4) is at all times in contact with the inner wall or shoulder of the groove 25, thereby preventing the lifter from accidentally rocking about the bead 11 and twisting off of the beaded rim of the lid.

The lifting key 16 or spreader, formed integrally with the lower edge of the wall 21 and at one end thereof, projects radially inward of the lid and takes under the bead 11 outwardly of the body portion 15 and channel 23. The key is flat and normally lies between and in a plane parallel with the beads 11 and 12 (Figs. 2 and 4). A lifting force applied to the finger piece causes movement of the key about a horizontal axis extending radially of the lid for spreading or separating the beads and thereby raising the lid. The lifting of the lever causes the lower outer edge of the key 16 to become the fulcrum point, the inner upper edge bearing on the under side of the bead 11 to move the lid to the broken line position shown in Fig. 2. Thus it will be noted, the entire lifting action of the key takes place directly beneath the bead. The inner end of the key terminates short of the end of the strip 20 of the body portion to provide a space equal to at least the diameter of the bead in order not to bind thereon as the lever is lifted to near vertical position. Complete removal of the receptacle lid when particularly tight fitting, requires at times more than one prying operation, thereby necessitating moving the lever to different points around the circumference, which may be readily accomplished by sliding the lever to the desired point.

In Fig. 5 the lever is shown applied to a single friction type plug, wherein a friction ring 26 is employed as a part of the can body 27. In this type of container, the key 16 bears directly on

the ring 26 and bead 11 as the lid 10 is forced upwardly.

The form of the invention illustrated in Figs. 6 and 7 is substantially similar to that previously described wherein an arcuately shaped channeled lever 30 overlies a peripheral bead 31 formed on a double friction type plug 32 or lid. The plug is adapted to seat in a friction ring 33 forming a part of the can body 34. The outer wall of the channeled lever 30 is provided at one end with a downwardly projecting cam 35 adapted to bear against the ring 33 and serve as a fulcrum for the lever. A key 36 formed adjacent the cam and rearwardly thereof, projects radially inwardly taking under the bead 31 whereby upon lifting the lever, the key and cam operate to raise the cover from the ring. A downwardly extending projection 37 formed on the inner wall of the lever opposite the cam 35 serves to retain it in operating position and prevent accidental dislodgement while the cover is removed.

Modifications may be resorted to within the spirit and scope of the appended claims.

I claim:

1. In combination, a pair of separably connected members at least one of which has a continuous peripheral bead in close proximity to the other member, a lever which is inverted U-shape in cross section and straddles said beads, means for holding the lever against rocking movement about its longitudinal axis and a spreader substantially at one end of the lever, said spreader normally projecting into the space between the bead and other member and operable upon swinging movement of the lever to further separate said bead and other member, said spreader consisting of a broad flat finger extending transverse to the length of the lever toward said means holding the latter against rocking.

2. In combination, a pair of separably connected members at least one of which has a continuous peripheral bead in close proximity to the other member, a lever which is inverted U-shape in cross section and straddles said bead, a finger at one end of the lever engaging the beaded member to secure the lever against rock-

ing movement about its longitudinal axis, a spreader substantially at said one end of the lever, said spreader extending transverse to the length of the lever and normally projecting into the space between the bead and other member and operable upon swinging movement of the lever to further separate said bead and other member.

3. In combination, a pair of separably connected members at least one of which has a continuous peripheral bead in close proximity to the other member, a lever which is inverted U-shape in cross section and straddles said bead, means for holding the lever against rocking movement about its longitudinal axis, means substantially at one end of the lever projecting into the space between the bead and other member and operable upon movement of the other end of the lever away from the bead for effecting further separation of said bead and other member, said means consisting of a broad flat spreader extending transverse to the length of the lever toward said means holding the latter against rocking, and an ear formed on the lever in proximity to said last named means and engaging one of said members to form a fulcrum about which the lever is moved.

4. In combination, a pair of separably connected members at least one of which has a continuous peripheral bead in close proximity to the other member, a lever which is inverted U-shape in cross section and straddles said bead, a finger forming a part of said lever for holding it against rocking movement about its longitudinal axis and a spreader substantially at one end of the lever, said spreader normally projecting into the space between the bead and other member transverse to the length of said lever and operable upon swinging movement of the lever to further separate said bead and other member, and an ear formed on the lever in proximity to said last named means and engaging one of said members to form a fulcrum about which the lever is moved.

HENRY E. FRANKENBERG.
